UNITED STATES PATENT OFFICE.

JOHN JOSEPH WALTER, OF NEW ALBANY, INDIANA.

METAL-CRIMPING MACHINE.

No. 901,131.

Specification of Letters Patent.

Patented Oct. 13, 1908.

Application filed August 5, 1907. Serial No. 387,150.

To all whom it may concern:

Be it known that I, JOHN JOSEPH WALTER, a citizen of the United States, residing at New Albany, in the State of Indiana, have 5 invented certain new and useful Improvements in Metal-Crimping Machines; and I do declare the following to be a full, clear, and exact description of the invention, such as will enable others skilled in the art to which 10 it appertains to make and use the same.

This invention relates to an improved metal-crimping machine.

The object of the invention is to provide a machine which will turn a double bent edge 15 in a metal sheet in one operation, thereby economizing at least one-half the time heretofore required for making a strong water-proof seam without the use of solder.

In the accompanying drawings,—Figure 1 20 represents a front elevation of this improved machine showing a sheet of tin after it has been crimped, partly removed therefrom; Fig. 2 represents an end elevation thereof; Fig. 3 represents a rear elevation; Fig. 4 represents a transverse section with the plunger 25 in operation bending a sheet; Fig. 5 represents a top plan view of the machine.

In the embodiment illustrated, end supports 1 and 2 are shown having oppositely disposed obliquely arranged slots, as 3, in which are mounted bearing ends 4 and 5 of a transversely sliding plunger 6, having its upper front edge beveled at 7. This plunger 6 is mounted between inclined guides, the 35 lower one 8, of which is formed of an obliquely disposed cross bar, which extends the entire length of the plunger and is fixedly secured at its opposite ends to two members 15 and 16 pivotally connected at one end at 15' to the end supports 1 and 2, and the upper edge 40 of this bar 8 is beveled to fit the beveled edge of a mandrel hereinafter described. The upper guide is formed of strips, as 9, which are also mounted on the pivoted members 15 and 45 16 and arranged parallel with the ends of the board 8 and spaced therefrom a sufficient distance to receive the ends of the plunger 6 and permit it to slide freely therebetween. Extending from the ends of the plunger 6 50 and projecting through the members 15 and 16 and slots as 3 in the end members are two bearing studs, as 10, on which are mounted two levers, as 11, pivotally connected at one end to the supports 1 and 2. Levers as 12 55 are pivotally connected at one end with the lower ends of the levers as 11. These levers

as 12 are pivoted eccentrically at their other ends to the outer ends of stub shafts 13 and 14 revolvably mounted in bearings in the members 15 and 16. The inner ends of these 60 shafts 13 and 14 have cam disks or members 17 and 18 fixed thereto, and these disks are provided with laterally extending arms 19 and 20 to which a folding member or leaf 21 is secured at its ends. This leaf 21 has a handle 65 22 for raising and lowering it. The cam disk 18, its adjacent shaft and the member 15 are provided with a radially extending cut-out portion 18' to permit the metal sheet after it is bent to be slipped out longitudinally therethrough.

Supported in the end members 1 and 2 below the leaf bearings or stub shafts 13 and 14 are two roller bearings 23 and 24 on which the cam disks 17 and 18 rotate. A stop bar 75 25 is arranged across the machine to limit the downward movement of the leaf 21.

Secured intermediate of its ends to the plunger 6 is a longitudinally arranged leaf-spring 26, the free ends of which bear on the 80 free ends of two pivoted levers 27 and 28, arranged at opposite ends of the plunger to hold said levers against the plunger to provide the proper tension therefor.

A mandrel 30 is fixed to the end members 85 1 and 2 and has its lower edge beveled at the rear side thereof, said beveled portion terminating in a laterally extending flange 31, which is preferably formed by cutting away the inner face of the mandrel above said 90 flange. This mandrel 30 is arranged above and spaced from the board 8 with its lower front edge arranged adjacent the inner edge of the leaf 21, but spaced therefrom a sufficient distance to permit a sheet of tin or 95 other metal to be crimped to be inserted between said leaf and the lower edge of the mandrel. The inner edge of the flange 31 of the mandrel is arranged adjacent the beveled edge of the plunger 6, and said plunger is 100 adapted to ride over said flange when the machine is in operation.

In the use of this machine the sheet of metal is slipped in between the lower edge of the mandrel 30 and the upper edge of the 105 clamping board 8 and extends over the beveled edge of the plunger at the distance which is desired to form the first bend near the edge thereof. The leaf 21 is then raised upwardly, which causes the cams 17 and 18 110 to ride on the rollers 23 and 24 and lift the pivoted members 15 and 16, thereby causing

the beveled edge of the board 8 to clamp the metal sheet between it and the mandrel and securely hold it in position while being bent. At the same time the plunger 6 is moved forwardly over the flange 31 on the mandrel 30 by means of the levers heretofore described, and a double bend is formed in the metal sheet by the edges of the plunger 6 and of the leaf 21, as is clearly shown in Fig. 4, the sheet 10 being folded upon itself and the edge of said folded portion turned under or inward to form a hem-like bend.

I claim as my invention:—

1. In a metal crimping machine, the combination of a supporting frame, an obliquely disposed mandrel mounted in said frame and having its lower edge beveled on the rear face thereof, said beveled face terminating in a forwardly extending lateral flange, an obliquely disposed plunger mounted to move at right angles to the rear face of said mandrel and slideable over the flange thereof, and a folding member mounted to coöperate with the front edge of said mandrel to form one 20 bend in the metal sheet, being operated on and connected to operate said plunger in forming another bend.
2. In a metal crimping machine, the combination of a supporting frame, an obliquely disposed mandrel mounted in said frame and having its lower edge beveled on the rear face thereof, said beveled face terminating in a forwardly extending lateral flange having a downwardly inclined lower face, an obliquely disposed plunger mounted to move at right angles to the rear face of said mandrel and slideable over the flange thereof, a folding member mounted to coöperate with the front edge of said mandrel to form one 30 bend in the metal sheet, being operated on and connected to operate said plunger in forming another bend.

and connected to operate said plunger in forming another bend, and a slot formed in one side of the frame to permit the removal of the metal sheet longitudinally there-through after crimping thereof.

3. In a metal crimping machine, the combination of spaced end supports having downwardly and rearwardly inclined obliquely arranged slots, a plunger arranged to move between said supports and having 50 studs projecting through said slots, levers pivoted at one end to the outer faces of said supports and connected with said studs, a folding member journaled in said supports, links connected at one end to the front ends 55 of said levers and at the other end with said folding member, and a mandrel arranged above and between said folding member and plunger.

4. In a metal crimping machine, the combination of spaced end supports, a plunger mounted to slide obliquely between said supports, levers pivoted at one end to said supports with their free ends bearing on said plunger, a spring member secured intermediate of its ends to said plunger and bearing on the free ends of said levers, a mandrel arranged above and adjacent to the upper edge of said plunger, a vertically movable folding member arranged to coöperate with said mandrel in forming a bend in the metal to be crimped, and means connecting said folding member and plunger.

In testimony whereof I have hereunto set my hand in presence of two subscribing witnesses.

JOHN JOSEPH WALTER.
